Primary Examiner — Garth Rademaker*Assistant Examiner* — Salamah Jordan(74) *Attorney, Agent, or Firm* — Neal, Gerber & Eisenberg LLP(57) **CLAIM**

The ornamental design for a gaming system, as shown and described.

DESCRIPTION

FIG. 1 is at front perspective view of a gaming system showing our new design.

FIG. 2 is a front view of the gaming system of FIG. 1.

FIG. 3 is a rear view of the gaming system of FIG. 1.

FIG. 4 is a right side view of the gaming system of FIG. 1.

FIG. 5 is a left side view of the gaming system of FIG. 1.

FIG. 6 is a top view of the gaming system of FIG. 1; and,

FIG. 7 is a bottom view of the gaming system of FIG. 1.

The broken lines in the figures illustrate portions of the gaming system that form no part of the claimed design.

1 Claim, 7 Drawing Sheets(56)
